UNITED STATES PATENT OFFICE

166,741

MICROPHONE OR THE LIKE

Alexander L. Dvorsky and Maurice Palo,
Conneaut, Ohio

Application January 10, 1951, Serial No. 13,738

Term of patent 7 years

(Cl. D26—14)

To all whom it may concern:

Be it known that we, Alexander L. Dvorsky and Maurice Palo, citizens of the United States, residing at Conneaut, in the county of Ashtabula and State of Ohio, have invented a new, original, and ornamental Design for Microphone or the like, of which the following is a specification, reference being had to the accompanying drawing, forming part hereof.

In the drawing:

Figure 1 is a plan view of a microphone embodying our invention; and

Figure 2 is a side elevation of the microphone of Figure 1.

The dominant features of the design are disclosed in full lines.

We claim:

The ornamental design for a microphone or the like, as shown and described.

ALEXANDER L. DVORSKY.
MAURICE PALO.
